CLAIM

The ornamental design for an electrostatic spray gun, as shown and described.

DESCRIPTION

FIG. 1 is a perspective view of a first embodiment of an electrostatic spray gun;

FIG. 2 is a front elevational view of the first embodiment of the electrostatic spray gun;

FIG. 3 is a rear elevational view of the first embodiment of the electrostatic spray gun;

FIG. 4 is a right side view of the first embodiment of the electrostatic spray gun;

FIG. 5 is a left side view of the first embodiment of the electrostatic spray gun;

FIG. 6 is a top plan view of the first embodiment of the electrostatic spray gun;

FIG. 7 is a bottom plan view of the first embodiment of the electrostatic spray gun;

FIG. 8 is a perspective view of a second embodiment of an electrostatic spray gun;

FIG. 9 is a front elevational view of the second embodiment of the electrostatic spray gun;

FIG. 10 is a rear elevational view of the second embodiment of the electrostatic spray gun;

FIG. 11 is a right side view of the second embodiment of the electrostatic spray gun;

FIG. 12 is a left side view of the second embodiment of the electrostatic spray gun;

FIG. 13 is a top plan view of the second embodiment of the electrostatic spray gun; and,

FIG. 14 is a bottom plan view of the second embodiment of the electrostatic spray gun.

The broken lines shown represent portions of an electrostatic spray gun and form no part of the claimed design.
